UNITED STATES PATENT OFFICE.

MARTIN B. SCHENCK, OF NEW HAVEN, CONNECTICUT, ASSIGNOR TO THE
YALE CASTER COMPANY, OF SAME PLACE.

DESIGN FOR A CASTER-FRAME.

SPECIFICATION forming part of Design No. 15,131, dated July 8, 1884.

Application filed February 16, 1884. Term of patent 7 years.

To all whom it may concern:

Be it known that I, MARTIN B. SCHENCK, a citizen of the United States, residing at New Haven, in the county of New Haven and State of Connecticut, have invented and produced a new and original Design for Two-Wheel Caster-Frames; and I do hereby declare that the following is a full, clear, and exact description of the same, reference being made to the accompanying drawings, in which—

Figure I is a perspective view of a caster-frame of my new design. Fig. II is a side elevation of the same. Figs. III and IV are respectively a top and under side view thereof.
15 The design consists in an ornamented shape of the frames or housings for two-wheel casters.

The principal feature of my design consists in the housing formed upon its front face with 20 a rounded or convex surface having rounded corners.

Such frames as ordinarily constructed have a plane perpendicular surface at A. I give

this portion of the frame a convex surface and round off the corners, as shown at B. The tail 25 or heel piece of the frame is a hollow spheroidal bulb or shell, C, having a contracted neck, D. Projecting downward from each side of the frame is a leg, E, and from the under side thereof a similar leg, E', all of which are 30 rounded off with gracefully-curving surfaces.

Having thus described my design for a frame for two-wheel casters, the following is what is claimed as new therein:

1. In a caster-frame, the design which consists of the housing having a convex front surface, A, and rounded corners B, as shown and described.

2. The design for a caster-frame, which consists of the housing having convex front surface, A, rounded corners B, spheroidal heel C, neck D, and legs E, as shown and described.

MARTIN B. SCHENCK.
